UNITED STATES PATENT OFFICE.

CHARLES D. BOWLUS, OF OHIO, ILLINOIS.

WINDMILL.

SPECIFICATION forming part of Letters Patent No. 274,261, dated March 20, 1883.

Application filed January 30, 1883. (No model.)

To all whom it may concern:

Be it known that I, CHARLES D. BOWLUS, of Ohio, in the county of Bureau and State of Illinois, have invented a new and Improved 5 Windmill, of which the following is a full, clear, and exact description.

My invention consists of the windmill mounted on a vertical tube that is bent above the bearing to an eccentric position for the turn-table of the wheel, enabling the wheel to shift around with the wind without the use of a tail-vane; and it also consists of improved contrivances for regulating the wheel to the force of the wind, all as hereinafter fully described.

Reference is to be had to the accompanying drawings, forming part of this specification, in which similar letters of reference indicate corresponding parts in all the figures.

Figure 1 is an elevation of the mill as seen 20 when looking from the windward side. Fig. 2 is a horizontal section of the wheel and top view of the rest, showing the position of the wheel when the wind is still or blowing lightly. Fig. 3 is a similar view, showing the position 25 of the wheel when it is turned around edge-wise to the wind; Fig. 4, a detail showing the supporting tube and arm in part and in section and the weighted regulating-lever in side elevation. Fig. 5 is a detail of the connecting- 30 rod for the crank, and Fig. 6 represents a portion of the upright supporting-tube in sectional elevation.

For the turn-table device I propose to employ an upright tube, *a*, fixed in suitable bearings, *b* *c*, in the upper part of the tower *d*, with the portion above the bearings bent at *e* eccentrically to the rest, and carrying a horizontal arm, *f*, at the top, extending a suitable distance from it, for carrying the wheel *g* in a 40 vertical plane with its shaft radial to the tube when the wheel is at rest in the still air or working lightly. The eccentric construction of the supporting-tube enables the wheel to be shifted around as the wind shifts by the direct 45 action of the wind on it, and thus avoids the need of a tail-vane.

For varying the angle of the wheel to the wind as the power of the wind increases, I mount the crank-shaft *h* in a bearing-plate, *i*, 50 that is pivoted at *j* to the outer end of the arm *f*, and has a short arm, *k*, extending from the

opposite side of said pivot, which is connected by rod *l* with the weighted lever *m*, pivoted to the top of arm *f*, near the tube *a*.

It will be seen that the weighted lever *m* 55 tends to maintain the wheel *g* in the position of Fig. 2, at right angles to the wind, indicated by the arrow; but as the power of the wind increases, the effect on the larger area of the wheel on one side of the pivot *j* will be to cause 60 the wheel to swing toward the position of Fig. 3, where it "feathers" the wind, so as to be inoperative thereby.

The lever *m* has a vertical arm, *n*, rising over the mouth of the upper end of the tube 65 *a*, and having a rod, *o*, connected to it, which extends down through the tube for being used to pull the wheel around out of the wind when it is to be stopped, said rod being connected to the arm by a kind of ball-joint *p*, allowing 70 the lever to vibrate. The rim *q* of the wheel is made to touch the tube *a* at the bend *e*, when swung out of the wind, to stop the rotation of the wheel by the friction.

The arm *f* has a branch, *t*, along which the 75 bearing-plate *i* traverses for support when the wheel swings on the pivot *j*. The connecting-rod *u* has oval or ball boxes, *w*, for connection with the crank, so as to allow the crank to swing as above described, and the lower 80 end of the rod is connected by a ball-joint, *x*, with an arm, *y*, that extends into the tube *a* through a slot in its side, and is swiveled to the upper end of the working-rod *z*. The rod *o* passes through the center of the swivel-joint. 85

The bent tube makes a simple and substantial turn-table, and the regulating apparatus is simple, cheap, efficient, and durable.

Having thus described my invention, what I claim as new, and desire to secure by Letters 90 Patent, is—

1. A wind-wheel mounted on a bent upright tube *a* for a turn-table, substantially as described.

2. The shaft of a wind-wheel, mounted on a 95 bearing-plate, *i*, pivoted to the supporting-arm at *j*, and connected by arm *k* and rod *l* with a weighted regulating-lever, *m*, substantially as described.

3. The weighted regulating-lever *m*, having 100 the pivoted wheel-shaft bearing connected to it, as set forth, and being arranged with rela-

tion to the turn-table axis, and having the stop-rod *o* connected to it, substantially as described.

4. The combination of supporting-tube *a*, arm *f*, pivoted wheel-shaft bearing *i*, and weighted regulating-lever *m*, substantially as described.

5. The combination of arm *f*, branch *t*, bearing-plate *i*, wheel-shaft *h*, pivot *j*, arm *k*, rod *l*, 10 weighted lever *m*, and the supporting-tube *a*, substantially as described.

6. The wheel-shaft *h*, mounted on shifting bearing-plate *i*, and being connected with the rod *z* by the rod *u*, having oval boxes *w* for the crank and ball-joint connection *x* with the 15 arm *y*, said arm being swiveled to rod *z*, substantially as described.

CHARLES D. BOWLUS.
